UNITED STATES PATENT OFFICE

146,935

DESIGN FOR A PICTURE PROJECTOR

Arthur J. Bradford, Wilmette, Ill., assignor to
Motion Picture Engineering Corporation, Chi-
cago, Ill., a corporation of Illinois

Application February 12, 1946, Serial No. 126,489

Term of patent 14 years

(Cl. D61—1)

To all whom it may concern:

Be it known that I, Arthur J. Bradford, a citizen of the United States, residing at Wilmette, in the county of Cook and State of Illinois, have invented a new, original, and ornamental Design for Picture Projector, of which the following is a specification, reference being had to the accompanying drawings, forming part thereof:

Figure 1 is a perspective view of one side and rear of the projector showing my new design.

Figure 2 is a perspective side and rear view taken from the opposite side of the projector.

Figure 3 is a perspective view showing the front of the projector.

I claim:

The ornamental design for a picture projec-
tor, substantially as shown.

ARTHUR J. BRADFORD.
